UNITED STATES PATENT OFFICE.

JAMES DOUGLAS BOYLAN, OF ANN ARBOR, MICHIGAN.

TOBACCO-CAN.

1,148,947.

Specification of Letters Patent. Patented Aug. 3, 1915.

Application filed October 13, 1914. Serial No. 866,432.

To all whom it may concern:

Be it known that I, JAMES D. BOYLAN, a citizen of the United States, and a resident of Ann Arbor, in the county of Washtenaw and State of Michigan, have made certain new and useful Improvements in Tobacco-Cans, of which the following is a specification.

My invention is an improvement in tobacco cans, and has for its object to provide a can of the character specified, especially adapted for holding paper cartons of tobacco, such as smoking tobacco, and wherein the can is provided with means adapted to be connected with the carton and with the can, for holding the carton in such position that access may be easily had to the tobacco.

In the drawings: Figure 1 is a perspective view of the improved can, Fig. 2 is an enlarged vertical section, Fig. 3 is a section on the line 3—3 of Fig. 2, Fig. 4 is a perspective view of the lower portion of a carton and the holder for the same.

In the present embodiment of the invention the can comprises a body 1 of elliptical cross section having a bottom 2 secured to the lower end thereof, and having a cover 3 at the upper end. The cover is provided with a marginal flange 4 fitting outside of the body, and the said cover may be hinged to the body if desired, or merely seated thereon. The tobacco, indicated at 5, is held in the usual paper carton 6, and the body of the can is shaped to fit and receive the carton.

The body of the can is provided at each end with a series of transverse corrugations 7, the said corrugations forming ribs on the inner and the outer surface of the body. The corrugations may be formed in any manner desired, and the corrugations of each series are spaced apart at equal distances from each other. It will be noticed that the corrugations extend across the side edges of the body, and are not continued to the opposite sides of the same. These corrugations are at the center of the body, and cover about one-third of the height of the can.

A plate 8 of resilient material is provided for connecting the carton with the can, and the said plate is shaped to fit within the can. The plate is provided at each end with a longitudinally extending reduced lug 9, for engaging the corrugations 7, and the said plate is of such length that when the lugs 9

are in engagement with the spaces between the ribs at each end of the can, the body of the plate will be arched or bowed, and this arch or bow is upward. The lower end of the carton is seated on the plate at the center thereof, as shown in Fig. 2, and preferably the carton is connected to the plate by means of the strip 10. The said strip may be of any suitable material, and the ends thereof are connected with the sides of the carton by an adhesive of any desired character. The body of the strip is passed beneath the plate 8 so that the plate is between the bottom of the carton and the body of the strip, and the carton is thus held to the plate by the strip.

Tobacco cans of the character in question are of slight width as a rule, so that when a portion of the contents of the carton is removed, the surface of the tobacco in the carton will be below the level of the top of the can, and the user is liable to injure his fingers in thrusting them in this narrow space. The sharp edges of the can body are liable to cut the fingers, and in addition it is difficult to remove the proper amount of tobacco with the usual construction of can. In the present construction, however, as the tobacco is used, the plate 8 may be moved upward, the ends slipping over the corrugations, to bring the surface of the tobacco toward the top of the can, and the excess paper of the carton may be torn off and thrown away.

It will be noted that the corrugations are so arranged that the ribs formed inside the can face upward, to permit the easy movement of the plate 8 upward, while making the downward movement impossible without releasing the plate at one end or springing the same. After the tobacco has been exhausted the plate is easily detached ready for the next carton.

The strip 10 may be a gummed sticker, of paper or the like, and it will be evident that any strip of paper having its ends gummed will suffice for this purpose.

In use, when the carton is first inserted in the can, the plate occupies a position against the bottom of the carton, being connected thereto by the strip 10, and the position of the plate is such that the top of the carton will be flush with the top of the body of the can, so that when the cover is opened free access may be had to the contents of the carton. As the tobacco is used, the plate is

slipped upward, and since there is no particular impediment to the upward movement of the plate, it may be moved in any desired manner, as for instance by pulling 5 upward on the excess paper of the carton. As the carton moves the plate will move also, the ends slipping over the ribs, which are similar to ratchet teeth. The carton may thus be moved upward, until the last of the 10 tobacco is removed. Whenever the carton is moved upward the excess paper at the top is torn away, so that the carton top is approximately flush with the top of the body of the can.

15 I claim:

1. A tobacco can for holding a paper carton of tobacco, said can being shaped to fit and receive the carton, and having a cover for closing the can, said can having at its 20 opposite ends transverse corrugations forming internal ribs, and a plate of resilient material adapted to fit within the can and having longitudinal extending lugs at its ends for engaging the ribs, said plate being of 25 greater length than the length of the can to cause the plate to take an arched or bowed

position in the can when the lugs are engaged with the ribs, and a strip of paper having its ends provided with an adhesive and adapted to be connected to the carton 30 and passing around the body of the plate intermediate the ends thereof to connect the carton and the plate, the ribs inside the can facing upward.

2. A tobacco can for holding a carton of 35 tobacco and shaped to fit and receive the carton of tobacco, the can having oppositely arranged internal series of transverse corrugations forming ribs, and a plate of resilient material adapted to fit within the can 40 and having lugs at its end for engaging the ribs and of greater length than the can to cause the plate to take an arched or bowed position in the can when the lugs are engaged with the ribs, and a connection between the plate and the carton intermediate 45 the ends of the plate for constraining the plate to move with the carton.
